US0D1057858S

(12) **United States Design Patent** (10) **Patent No.:** **US D1,057,858 S**
(45) **Date of Patent:** **** Jan. 14, 2025**

(54) **ELECTRONIC GRIP STRENGTH METER**

(71) Applicant: **Zhongyiheng Electronic Technology (Hangzhou) Co., Ltd.**, Zhejiang (CN)

(72) Inventor: **Zecheng Yu**, Zhejiang (CN)

(73) Assignee: **Zhongyiheng Electronic Technology (Hangzhou) Co. Ltd.**, Zhejiang (CN)

(**) Term: **15 Years**

(21) Appl. No.: **29/947,576**

(22) Filed: **Jun. 17, 2024**

(51) LOC (15) Cl. **21-02**

(52) U.S. Cl.

USPC **D21/662**; D10/83

(57) **CLAIM**

The ornamental design for an electronic grip strength meter as shown and described.

DESCRIPTION

FIG. 1 is a front, right and top perspective view of an electronic grip strength meter, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the electronic grip strength meter that form no part of the claimed design.

1 Claim, 8 Drawing Sheets
